UNITED STATES PATENT OFFICE

2,410,914

ORNAMENT FOR EARS

Hoke S. Williams, St. Petersburg, Fla.

Application January 31, 1945, Serial No. 575,376

6 Claims. (Cl. 63—14)

1

My present invention, in its broad aspect, has to do with improvements in supporting ear ornaments, and more particularly, it is my purpose to provide a slightly springy supporting or carrier frame which detachably fits into various forms of indentations in the anatomy of the ear. It will be noted on inspection of the exterior lobes of the ear that there are a number of indentations or crevices, one of the principal ones being about the ear canal, and I make use of this indentation and others to receive and mount my supporting frame for the ornament. The supporting frame is formed of springy wire, plastic or other material, and is shaped to conveniently fit indentations of the ear. I do not wish to limit myself to particular shapes, although I have developed preferred and most practical shapes and forms.

Other and equally important objects and advantages of my invention will be apparent from the following description and drawing, but it is to be understood that changes in form, size, shape, materials, construction and arrangement of parts are contemplated by my broad inventive concept, and are within the scope and purview of the appended claims.

In the drawing wherein I have illustrated a preferred form of my invention:

Figure 1 is a side view of a person wearing my invention.

Figure 2 is a view of the supporting frame bent similar to an S-shaped configuration.

Figure 3 is a view of a substantially C-shaped carrier frame construction.

Figure 4 is a view of a substantially half-moon shaped carrier frame construction.

Figure 5 is a view of an ear with the C-shaped carrier applied thereto, and

Figure 6 is a view of an ear with the half-moon shaped carrier applied thereto.

In the drawing wherein like characters of reference are used to designate like or similar parts:

It will be noted that the anatomy of the ear includes a substantially C-shaped natural indentation 2 about and spaced from the ear canal, and I have found this portion of the ear convenient to use for the purposes of my invention, thereby avoiding puncturing the lobe of the ear or the like.

My invention includes a spring wire, or plastic

2

or other metal carrier frame 3, which may be of substantially S-shape construction as shown in Figure 2. The carrier ends 9 are bent back against themselves to form guards, and an eye 10 is formed by bending the material of the carrier frame over and around between the reverse curves 10a of the S-formation. A C-shaped formation as shown in Figure 3 has a guarded end 11 and a gradually broadened flattened body 12 to which the ornament 6 is attached by a pin 13, or a half-moon shaped flattened body 14 may function as the carrier as shown in Figure 4, with the pin 15 located midway between the ends to mount the ornament 6. It will be noted that this form is relatively wide in the middle 16 and is curved at the bottom 17 and top 18 and decreases in width to the rounded off ends 19.

From the foregoing, it is believed that the operation and advantages of my invention will be apparent, but it is again emphasized that interpretation of the scope of my invention should only be conclusive when made in the light of the subjoined claims.

I claim:

- 25 1. An ear ornament, comprising a carrier frame shaped to fit into and be supported by indentations in the anatomy of the ear.
- 20 2. An ear ornament, comprising a curved carrier frame shaped to removably fit into and be supported by indentations in the anatomy of the ear.
- 30 3. An ear ornament, comprising a relatively springy carrier body bent to form an ornament support and a curved part to removably fit into and be supported by indentations in the anatomy of the ear.
- 35 4. The invention as defined in claim 3 wherein the carrier body is substantially S-shaped in configuration with the ends bent to provide guards, and the material of the body between the ends and between the lobes of the S-shaped configuration bent over and about itself to form an eye.
- 40 5. The invention as defined in claim 2 wherein the carrier frame is substantially C-shaped.
- 45 6. The invention as defined in claim 2 wherein the carrier frame is substantially half-moon shaped.

Hoke S. Williams.
